UNITED STATES PATENT OFFICE.

JAMES W. MARRIOTT, OF MANAYUNK, PENNSYLVANIA.

HYDROCARBON-BURNER.

1,183,998.

Specification of Letters Patent. Patented May 23, 1916.

Application filed August 20, 1913. Serial No. 785,685.

To all whom it may concern:

Be it known that I, JAMES W. MARRIOTT, a citizen of the United States, residing at Manayunk, in the county of Philadelphia 5 and State of Pennsylvania, have invented a new and useful Hydrocarbon-Burner, of which the following is a specification.

My invention relates to the class of hydrocarbon burners employing oil, coal-tar and 10 similar fluids as fuel, and more particularly relates to burners used in connection with boiler furnaces, heating furnaces, and similar apparatus.

One object of the invention is to provide 15 a burner of improved construction having novel means whereby the fuel used is gasified and is mixed with air or other oxygen bearing element and burned.

Another object of this invention is to provide 20 a burner having novel means whereby the mixing of the oil or other hydro-carbon and the air is regulated and controlled.

A still further object of my invention is to provide a burner having novel means for 25 supplying heated air for use in the mixture of air and hydro-carbon oil used in the burner and for regulating the temperature of the heated air used in connection with my improved burner.

Referring to the drawings forming part 30 of this specification, Figure 1 is a longitudinal section, showing the construction of my improved burner in detail.

Fig. 2 is a transverse section of the 35 burner, on the line II-II of Fig. 1. Fig. 3 is a sectional side elevation showing one manner of applying my improved burner for use on a furnace.

In the accompanying drawings, the number 40 2 designates the casing of my improved burner which, as shown, is telescoped over the hollow burner barrel 3. The nose or discharge end of the casing 2 is provided with internal screw threads which engage 45 with the external threads provided on the end of the barrel 3 in securing and holding the casing in position on the barrel of the burner. The rear end 2^a of the casing is enlarged in diameter and surrounds the enlarged rear end 3^a of the barrel 3 and a screw threaded nut 4 engages with the screw

threads 5 on the barrel 3 to hold the casing tightly in position on the barrel 3. Asbestos or other suitable packing material 6 is employed between the opposing faces of the 55 casing 2, barrel 3 and nut 4 to provide a tight joint between such parts and prevent leakage of the oil or other liquid fuel from the annular fuel chamber 7 formed between the casing 2 and barrel 3 by the walls 60 thereof.

In the barrel 3, adjacent to the discharge end of the burner, is a series of small radial openings 8 by which communication is afforded between the fuel chamber 7 and the 65 interior 9 of the hollow barrel 3 and through which openings the oil or other liquid fuel is discharged into the interior 9 of the barrel. An opening in the wall of the casing 2 is closed by means of a plug 10 to afford 70 means for inspecting and, if necessary, cleaning the openings 8 in the barrel 3 and an opening 11 in the rear end of the fuel chamber 7 is connected by means of a tube 12 with the fluid fuel supply, the fuel being 75 delivered into the tube 11 either by gravity or under pressure as found necessary or desirable. The valve 13 on the tube 12 provides means for regulating the supply of fuel to the fuel chamber. 80

Adjacent to the rear end of the enlarged portion 3^a of the barrel is a side outlet opening 14 through which heated air is introduced into the interior 8 of the barrel 3 when the burner is in operation and also 85 extending through an opening 15 in the rear end 3^a of the barrel is a small tube forming a nozzle 16 through which compressed air is delivered into the barrel to induce a flow of heated air through the opening 14 when 90 the burner is in operation. The rear end of the nozzle 16 is screw threaded into a nipple 17 which in turn is screw threaded in the opening in the rear of the barrel 3 and an elbow 18 inserted in the end of the nipple 95 17 provides suitable means for connecting the nozzle 16 with an air compressor or other source of air under pressure (not shown), the supply of compressed air being controlled by the valve 19 on the supply 100 pipe 20 which connects into the elbow 18.

As will be seen by reference to Fig. 3 the

discharge end of the burner projects into an opening 21 through the wall 22 of the furnace so as to discharge the burning or burned gases into the furnace chamber 23. 5 The opening 14 in the rear end of the burner is connected by means of a tube 24 with a T 25 and connected into one end of the T 25 is a pipe 26 which projects through an opening 27 into the furnace chamber 23. A valve 10 28 on the pipe 26 provides means for regulating the supply of heated gas drawn from the furnace through the pipe 26 into the pipe 24 and, through the inlet opening 14, into the interior of the burner barrel 3. 15 The heated gases drawn from the furnace through the pipe 26 may be air or heated products of combustion. The other side of the T 25 is provided with a valve 29 which opens into the atmosphere to provide means 20 for admitting a supply of air, at atmospheric pressure and temperature, into the pipe 24 and in this way regulate and control the temperature of the hot air passing through the pipe 24 into the burner. 25 In the operation of my improved burner the parts are assembled as shown in Fig. 3. The valves 13 and 19 controlling respectively the supply of oil and compressed air to the burner are then adjusted to admit air 30 into the nozzle 16 and oil into the fuel chamber 7. The oil in the chamber 7 enters through the openings 8 in the walls of the barrel 3 into the interior 9 of this barrel and is met by the incoming stream of compressed air passing through the barrel 3 and supplied by the nozzle 16. The mixture of air and oil or other hydro-carbon fuel is then discharged through the opening 21 into the furnace 23 and, being ignited, is burned 40 therein. The stream of compressed air passing at a high velocity from the nozzle 16 into the interior 8 of the barrel 3 induces a flow of air through the pipes 24 and 26 and the opening 14 into the chamber 9 and as 45 one end of the pipe 26 opens into the furnace chamber, heated air will be drawn from the chamber 23 into the chamber 9 of the barrel 3. The passage of the heated air through the barrel 3 will heat the walls thereof and 50 the liquid fuel contained in the fuel chamber 9 will become highly heated to such a temperature that the fuel becomes gasified upon emerging from the openings 8 into the chamber 9. By a suitable adjustment of 55 the valves 27 and 28 a supply of cold air is admitted into the T 25 which will regulate the temperature of the hot air delivered through the pipe 26 into the barrel 3 and in this way a more efficient operation of the 60 burner is obtained.

The advantages of my invention will be apparent to those skilled in the art. The apparatus is simple and is easily kept in repair. Modifications in the construction

and arrangement of the parts may be made 65 without departing from my invention.

I claim:

1. The combination with a furnace, of a hydrocarbon burner arranged to discharge into said furnace, said burner having a hollow burner barrel with an enlarged rear end forming a fluid chamber, a casing forming an annular fluid chamber surrounding said burner barrel, means connecting said annular chamber and the burner barrel to deliver 70 fluid fuel to said burner barrel, a nozzle connecting the first fluid chamber with a source of compressed air, a conduit connecting the latter chamber with the interior of the furnace, means controlling the supply 75 of compressed air to said first chamber whereby a flow of heated fluid is induced through said conduit, and means for controlling the volume of heated fluid delivered into said first chamber. 80

2. The combination with a furnace, of a hydrocarbon burner arranged to discharge into said furnace, said burner having a hollow burner barrel with an enlarged rear end forming a fluid chamber, a casing forming an annular fluid chamber surrounding said burner barrel, means connecting said annular chamber and the burner barrel to deliver 90 fluid fuel to said burner barrel, a nozzle connecting the first fluid chamber with a source of compressed air, a conduit connecting the latter chamber with the interior of the furnace, means controlling the supply of compressed air to said first chamber whereby a flow of heated fluid is induced 95 through said conduit, and means for controlling the volume of heated fluid delivered into said first chamber, and means for controlling the temperature of the heated fluid entering the burner. 100

3. A hydrocarbon burner having an axially horizontal burner barrel, a casing surrounding the barrel and forming an annular fuel chamber therewith, said barrel having at least one transverse opening in 110 the side wall thereof to connect the interior of the barrel with that of the casing, said casing having a screw threaded connection to one end of the barrel and the other end thereof in sliding engagement with the 115 barrel and a lock nut screw threaded on the barrel and adapted to engage with the sliding end of said casing. 120

4. A hydrocarbon burner having a burner barrel, a casing surrounding the barrel and 120 forming an annular fuel chamber therewith, said barrel having a plurality of transverse openings in the side wall thereof to connect the interior of the barrel with the interior of the casing, said casing having one end in 125 screw threaded engagement with the barrel with the other end thereof in sliding engagement on the barrel, a packing groove in the

sliding end of said casing, and a lock nut
screw threaded on the barrel and adapted
to engage with the sliding end of the casing
to hold the packing in said groove and pre-
5 vent leakage at the joint between the barrel
and sliding end of said casing.

In testimony whereof, I have hereunto set
my hand.

JAMES W. MARRIOTT.
